UNITED STATES PATENT OFFICE.

BENJAMIN BERNARD DEITEL, OF BROOKLYN, NEW YORK.

VANITY CASE.

Application filed July 11, 1928. Serial No. 291,809.

My invention relates to containers and, more particularly, to novelty containers and vanity cases.

The object of the invention is to simplify the construction of such containers while preserving a rugged structure and a neat and artistic appearance, the manner of putting the parts together being such as to eliminate many of the elements now used in the construction of such articles and to reduce the number of tools and dies in their manufacture.

In the drawing, Figure 1 is a perspective view of the preferred embodiment of my invention, viz., a container simulating a book, this figure showing the container as closed; Figure 2 is a plan view of the same container when open; Figure 3 is a cross section of the same container taken along the line 3—3 of Figure 1; and Figure 4 is a fragmentary perspective view of the same container with certain parts unassembled, in order to elucidate the construction.

Referring to the figures in detail, 1 is an open frame made of sheet metal and constituting the four walls of a container designed to simulate a book, the front and the two end walls representing the front and the end leaf edges of the book. At its nether periphery, frame 1 is bent to provide outwardly projecting flanges 2 on three sides, viz., at the front and at the two ends of the "book". A second frame 2', also open, but flat, is hinged to the back wall of frame 1 in any standard fashion, as by means of the hinge 6. The frame 2' is simply a square piece of sheet metal having a square hole cut out of it so as to leave edges somewhat wider than the flanges 2 of frame 1. Each frame is provided with a cover plate, preferably also of sheet metal, the cover plate 3 forming the bottom, and the cover plate 3' the top, of the container. To the two cover plates 3 and 3' is secured a facing 4, preferably made of leather, to simulate the leather cover of a book, which extends over the entire surface of the two cover plates and over the back wall of frame 1. The cover plates 3 and 3', together with the facing 4, are held in place by means of the channel members 5, 5, which extend over the front and the two ends of the "book" and firmly clamp the cover plate 3 with the facing, to the flanges 2 of frame 1, and the cover plate 3' with the facing to the edges of frame 2'. The walls of frame 1 may be provided with additional but inwardly projecting flanges 7. The space formed

by the frame 1 and cover plate 3 may be divided into compartments. In the illustration shown in Figure 2, which is designed for a vanity case, two shallow pans 9 and 10 are set within this space, one being for powder and the other for rouge, the two pans being separated by a cross piece 11 which also serves to hold the two pans in place. The usual pads may also be provided, as is indicated on the drawing in dotted lines and the numerals 12 and 13. A mirror 15, set within the bezels 14 formed by the inward edges of frame 2', rests against the cover plate 3'. The bezels 14 are so spaced that when the container is closed they can pass the inwardly projecting flanges 7 of frame 1. A spring lock or catch 8 is shown in Figures 2 and 3, to hold the cover plate 3' down when the container is closed. The facing 4 is turned inwardly at 16 in a manner similar to that used in book binding.

While I have illustrated my invention as applied to a vanity case shaped to simulate a book, clearly, the construction shown is applicable to containers of different shape and for different purposes, the main feature of the invention residing in the formation of a box by making an open frame to serve as its walls and connecting one or two covers (bottom alone, or top and bottom) to the frame in the manner described, this construction being exceedingly simple and cheap and requiring very few tools and dies for its manufacture.

I claim:

1. A container made of two parts, one of said parts comprising an open frame constituting the walls of said container, and the other part comprising a flat open frame hinged to said first mentioned frame, outwardly projecting flanges on said first mentioned frame at one of its peripheries, a cover plate conforming to the shape of said first mentioned frame and constituting the bottom of said container, a cover plate conforming to the shape of said flat open frame and constituting the top of said container, a facing extending over said cover plates and over the hinged portions of said frames, a separate channel member clamping said facing and said bottom cover plate to said flanges, and a separate channel member clamping said facing and said top cover plate to the edges of said flat open frame.

2. A container simulating a book made of two parts, one of said parts comprising an

- open frame constituting the walls of said container, the front and the two end walls representing the front and the end leaf edges of said book, and the other part comprising a flat open frame hinged to the back wall of said first mentioned frame, outwardly projecting front and end flanges on said first mentioned frame along one of its peripheries, inwardly projecting flanges along its other periphery, a cover plate conforming to the shape of said first mentioned frame and constituting the bottom of said case, a cover plate conforming to the shape of said flat open frame and constituting the top of said case, bezels along the inner edges of said flat frame to hold a mirror against the cover plate thereof and fitting within the inwardly projecting flanges of said first mentioned frame, a facing extending over said cover plates and over the back wall of said first mentioned frame simulating the cover of a book, a separate channel member clamping said facing and said bottom cover plate to said flanges the entire length thereof, and a separate channel member clamping said facing and the front and end edges of said top cover plate to the corresponding edges of said flat open frame.
3. A vanity case simulating a book and made of two parts, one of said parts comprising an open frame constituting the walls of said case, the front and the two end walls representing the front and the end leaf edges of said book, and the other part comprising a flat open frame hinged to the back wall of said first mentioned frame, outwardly projecting front and end flanges on said first mentioned frame along one of its peripheries, inwardly projecting flanges along its other periphery, a cover plate conforming to the shape of said first mentioned frame and constituting the bottom of said case, a cover plate conforming to the shape of said flat open frame and constituting the top of said case, bezels along the inner edges of said flat frame to hold a mirror against the cover plate thereof and fitting within the inwardly projecting flanges of said first mentioned frame, a facing extending over said cover plates and over the back wall of said first mentioned frame simulating the cover of a book, a separate channel member clamping said facing and said bottom cover plate to said outwardly projecting flanges the entire length thereof, and a separate channel member clamping said facing and the front and end edges of said top cover plate to the corresponding edges of said flat frame.

BENJAMIN BERNARD DEITEL.
